Primary Examiner — W. A. Teddy Falloway*Assistant Examiner* — Amanda Kay Birdwell(74) *Attorney, Agent, or Firm* — Taylor J. Ross(57) **CLAIM**

The ornamental design for a manual carry strap, as shown and described.

DESCRIPTION

FIG. 1 is a top, front and right side isometric view of a manual carry strap showing my new design;

FIG. 2 is a bottom, rear and left side isometric view thereof;

FIG. 3 is an enlarged top plan view thererof;

FIG. 4 is an enlarged bottom plan view thereof;

FIG. 5 is a front elevation view, the rear elevation being identical thereto;

FIG. 6 is a right side elevation view, the left side elevation being identical thereto; and,

FIG. 7 is a cross-sectional view thereof, taken along and in the direction of line 7-7 of FIG. 3.
